United States Patent Office.

DAVID W. WRIGHT, OF NEW YORK, N. Y.

Design No. 3,185, dated August 25, 1868.

DESIGN FOR POCKET SUN-DIAL.

The Schedule referred to in these Letters Patent and making part of the same.

TO ALL WHOM IT MAY CONCERN:

Be it known that I, DAVID W. WRIGHT, of the city of New York, in the county of New York, and State of New York, have originated a new Form or Configuration of Shape of Case for Pocket Sun-Dials, of which the following is a full, clear, and exact description, reference being had to the accompanying drawings, making part of this specification, the figure marked A representing the face of the case, figure B the back of the case.

The nature of my invention consists in making the case for sun-dials in the shape and form of a watch-case, with the words "solar watch" thereon.

What I claim as my invention, and desire to secure by Letters Patent, is—

The design of a pocket sun-dial case, as shown and described.
